United States Patent Office

Des. 191,720

Patented Nov. 7, 1961

191,720

LUGGAGE LOCK OR SIMILAR ARTICLE

Charles S. Gehrie, Montclair, N.J., assignor to Presto
Lock Co., Garfield, N.J., a limited partnership

Filed Oct. 8, 1959, Ser. No. 57,856

Term of patent 14 years

(Cl. D50—7)

FIG. 1

FIG. 2

FIG. 1 is a front elevational view of a luggage lock or similar article embodying my new design; and

FIG. 2 is a side elevational view of the same.

The dominant feature of my design resides in the full line showing.

I claim:

The ornamental design for a luggage lock or similar article, as shown and described.
